Application September 21, 1949, Serial No. 116,924

4 Claims. (Cl. 64—25)

1

This invention relates to couplings for rotatable parts and more particularly to couplings which permit limited relative rotation of said parts.

An object of the present invention is to provide a novel speed responsive device for drivably coupling two rotatable parts.

Another object of the invention is to provide a novel coupling of the centrifugally responsive type for connecting and varying the angular relationship of a pair of rotating members.

A further object is to provide a device of the above character which is of small size and weight and which is well adapted for use in automatically controlling the timing of the sparks in the ignition system of an engine.

Still another object is to provide a shaft coupling of the above type which embodies only a small number of simply constructed parts which may be readily and easily assembled to function in a novel manner and in a relatively small space to adjust the relative angular positions of the parts connected thereby.

A still further object is to provide a novel coupling which will effect a plurality of variations in the angular relation of the connected parts at different predetermined speeds of rotation as the speed of rotation increases.

Another object is to provide a device of the above character which is novelly constructed in such a manner as to reduce the length of the centrifugal weights and increase the bearing surface therefor without adversely affecting the available force for effecting the desired result.

A further object is to provide a novel coupling means of the above type which may be readily and quickly assembled or reassembled in such manner as to obtain the same relative movement of the driving and driven parts for either direction of rotation.

The above and further objects and novel features of the invention will more fully appear from the following detailed description when the same is read in connection with the accompanying drawings. It is to be expressly understood, however, that the drawings are for the purpose of illustration only and are not intended to define the limits of the invention, reference for this latter purpose being had primarily to the appended claims.

In the drawings, wherein like reference characters refer to like parts throughout the several views,

Fig. 1 is an end elevation view, looking toward the right in Fig. 2, of one form of coupling comprehend by the invention;

2

Fig. 2 is a sectional side elevation view of said device, the section being taken substantially on line 2—2 of Fig. 1;

Fig. 3 is a detail view, with parts broken away and sectioned, of one set of flyweights, the view being taken on line 3—3 of Fig. 4; and

Fig. 4 is an exploded view of the device of Fig. 2, partly in section and with parts broken away, and with the nearest set of flyweights removed.

10. A single embodiment of the invention is illustrated in the drawings, by way of example, in a form adapted for use in controlling the angular relationship of two rotating parts, such as a circuit breaker cam or distributor finger of an engine ignition system and the drive shaft therefore. In such a construction, the coupling shown is effective to automatically advance and retard the occurrence of the ignition spark in relation to the position of the engine pistons in the cylinders and in response to the speed of the engine. Although the device may be driven from either end, for the purpose of simplifying the description the left hand member, as viewed in Figs. 2 and 4, will be considered to be the driving member.

15. In the form shown the simplified coupling comprises a driving member or assembly 10, one or a pair of flyweight assemblies 11 and a driven member or assembly 12. The driving assembly includes a tubular hub 14 which is provided with a keyway 15 by means of which the same may be drivably connected to a power shaft (not shown). Extending radially from hub 14 is a flange that may be in the form of a disk 16. The hub and disk may be integral or otherwise suitably secured together. A pair of diametrically disposed stub shafts or bearing pins 17, 18 are secured to and project axially from flange 16 near the periphery thereof. The driven assembly is similarly constructed and comprises tubular hub 19, flange or disk 21, and pivot pins or stub shafts 22, 23. The latter and pins 17, 18 may be secured in place by forming over and riveting the ends thereof against disks 21 and 16, respectively, but any other suitable known means of fastening the same may be employed. When the driving and driven members are assembled with each other, hub 19 has a sliding fit on hub 14 (Fig. 2) so that said members may move angularly relative to each other.

20. In the interest of better mechanical balance two centrifugal flyweight assemblies are provided although only one is essential. Since both these assemblies are of identical construction only one will be now described in detail. Each assembly 11 comprises two weights 24, 25 which may be of

identical construction to thereby minimize the number of different parts and hence benefit from the several known advantages accruing from such duplication of parts. The reduced ends 26, 26' of the weights overlap and are drilled to receive a pivot pin 27 whereby the same are pivotally connected together. This connection is very beneficial in preventing bending of the weights and vibration thereof during operation of the coupling. The other or large ends of the weights are also transversely bored—one for receiving a supporting pin 17 on driving assembly 10 and one for receiving a pin 22 on driven assembly 12. It will be noted that the pins 17 and 22 provide long bearing surfaces for the weights and hence prevent lateral vibration of the latter. The second set of centrifugal weights 24' and 25' (partially shown only in Fig. 1) is mounted on driving pin 18 and driven pin 23.

The pivotally connected weights 24, 25 are normally held in the extended position shown in Fig. 3 by resilient means combined therewith in a novel and simplified manner to take fullest advantage of the space available and to provide what may be called a plural step operation of the centrifugal weights during rotation. Said means, as shown, comprises two simple leaf springs 28 and 29 mounted by common means in spaced relation to each other on the inner face of weight 24 adjacent the axis of rotation. Both springs are held in place in the groove 30 in the inner face of said weight by a single set screw 31 threaded into a tapped hole in the weight. The anchored ends of the springs are held in spaced relation by shims or washers 32.

Spring 28, which is shown as being the shorter of the two, extends across the pivotal connection 27 and engages the bottom of the groove 33 in weight 25, exerting a pressure which tends to hold the weights in the relative positions illustrated. As will more fully appear hereafter, this pressure may be of any desired magnitude or the assembly may be such that no pressure is exerted by spring 28 until the connected ends of the weights are caused to move outwardly away from the axis of rotation (to the right in Fig. 3) to thereby cause the remote ends of the weights on pins 17 and 22 to approach each other. Spring 29 also extends across pivot 27 but the free end thereof does not contact weight 25 until the weights have moved a predetermined amount against the pressure of spring 28 in the manner described in the preceding sentence. This movement of the weights is limited by a slot 34 in disk 16 into which an extended portion 35 of pivot pin 27 projects to act as a stop. The pins 27, 35 engage the elongated side walls of slots 34 and the latter are elongated to provide for assembly suitable for either direction of rotation as pointed out hereafter.

It will thus be seen that when the units of Fig. 4 are in assembled relation (Figs. 1 and 2), one end of the flyweight assembly is pivotally connected at pin 17 to the driving unit 10 and the other end is similarly connected to the driven unit 12 at pin 22. Accordingly, upon rotation of the driving unit in a clockwise direction as viewed in Fig. 1, a pull will be exerted through linkage 24, 25 upon the driven unit so that said units will rotate together. This pulling action tends to separate, as far as possible, the remote ends of the two weights that are supported on pins 17 and 22 and thereby supplement the action of spring 28.

As the speed of rotation increases, centrifugal

force tends to throw the ends of the weights 24 and 25 connected by pin 27 outwardly from the axis of rotation, the same pivoting about pins 17 and 22. When this force is sufficient to overcome the opposing forces including the resistance of spring 28, the adjacent ends of the weights will move outwardly from the axis thereby decreasing the acute angle between lines joining the center of pivot 27 with the centers of pivots 17 and 22 and thus causing the latter pivots to move closer together. This effects relative rotation of the driving and driven units and continues until spring 29 engages weight 25 and exerts a sufficient pressure to arrest the articulating movement of the weights. After a further increase in speed and hence in the effective centrifugal force, the initial pressure of spring 29 will be overcome and further relative angular movement of the driving and driven units will be effected. The exact nature of the relative movement which is thus effected may be varied by the selection of springs having desired characteristics. When the speed decreases the reverse action will take place. With the parts assembled in the manner described, the driven unit 12 will be caused to advance in relation to driving unit 10 during increases in speed in the direction of the arrow in Fig. 1. If the same results are desired for the opposite rotation, it is only necessary to mount the weight 24 on pin 18 and weight 25 on pin 23. In other words the leading weight (rotation-wise) of each set should be mounted on a pivot pin secured to the driving unit 10 and the trailing weight of each set should be pivotally mounted on the driven unit 12.

It will be understood that springs 28 and 29 may be so calibrated and positioned that predetermined relative movements of assemblies 10 and 12 may be effected during predetermined ranges of speeds of rotation. Although the springs may be so constructed as to permit gradual changes in the angular relation of said units in accordance with changes of speed, it may be preferable in some installations that the springs be such as to permit relatively abrupt or sudden changes of predetermined angular extent whenever preselected speeds are attained.

There is thus provided a highly efficient and effective coupling for connecting rotating parts in such manner as to automatically effect relative angular movement of said parts in accordance with the speed of rotation. The novel construction provided results in a device which is mechanically simple and yet rugged and small in comparison to devices heretofore provided for the same purpose. The total number of parts required is small and the number of different kinds of parts is considerably smaller than the total, thereby greatly reducing the manufacturing cost and facilitating assembly. The space requirements of the present device are less than other comparable devices and in operation it is substantially free of vibration and chattering, thereby enhancing its dependability and accuracy.

Although only a single embodiment of the invention has been illustrated in the accompanying drawing and described in the foregoing specification, it is to be expressly understood that the same is not limited thereto. For example, more or less than two sets of centrifugal weights may be employed and more or less than two springs may be used on each set of weights. Various other changes may be made in the design and arrangement of parts illustrated without departing from the spirit and scope of the invention.

as will now be understood by those skilled in the art. For a definition of the limits of the invention reference is had primarily to the appended claims.

What is claimed is:

1. In apparatus of the class described, a driving member, a driven member free for angular movement relative to said driving member, coupling means for drivably connecting said members comprising a pair of centrifugally actuatable weights, means pivotally connecting one of said weights adjacent one end thereof to said driving member, means pivotally connecting the other of said weights adjacent one end thereof to said driven member and means pivotally connecting the other ends of said weights to each other, the axes of said pivotal connecting means being substantially parallel to the axis of rotation of said driving member, and resilient means for resisting pivotal movement of said weights in one direction about the pivotal connecting means therefor, said resilient means comprising at least two leaf spring means having corresponding ends thereof secured to said one weight, said secured ends being spaced from each other in the direction of said axis of rotation from said one weight, the unsecured portions of said spring means extending from said secured ends in substantially parallel relation to each other, and said spring means being of different lengths with the longer spring means spaced further than the shorter spring means from the weights toward said axis of rotation, the free end of the shorter spring means being normally in sliding engagement with a surface of said other weight and the free end of the longer spring means being normally spaced from said other weight but adapted to engage said surface of the latter at a place beyond the end of the shorter spring means when the weights have been moved a predetermined amount by centrifugal force, said surface of said other weight being one which faces toward said axis of rotation and each said spring means being unconfined and free to flex throughout the length of said unsecured portion thereof.

2. In apparatus of the class described, a driving member, a driven member free for angular movement relative to said driving member, and coupling means for drivably connecting said members comprising a set of pivotally connected centrifugal weights pivotally connected to said members, whereby articulation of said weights effects relative angular movement of said members, means secured to one of said weights and engageable with the other of said weights for yieldably resisting articulation of said weights in response to centrifugal force, and stop means for limiting articulation of said weights comprising means pivotally connecting the weights and engageable with one of said members.

3. In apparatus of the class described, a driving member, a driven member free for angular movement relative to said driving member, coupling means for drivably connecting said mem-

bers comprising a pair of centrifugally actuatable weights, means pivotally connecting one of said weights adjacent one end thereof to said driving member, means pivotally connecting the other of said weights adjacent one end thereof to said driven member, means pivotally connecting the other ends of said weights to each other, the axes of said pivotal connecting means being substantially parallel to the axis of rotation of said driving member, and resilient means for resisting pivotal movement of said weights in one direction about the pivotal connecting means therefor, said resilient means comprising a leaf spring rigidly secured at one end to one of said weights and having the other end portion thereof in sliding engagement with the other of said weights to yieldably resist movement of said weights in response to centrifugal force, and stop means for limiting articulation of said weights, said stop means including an extension on the means pivotally connecting the ends of said weights to each other engageable with one of said members.

4. In apparatus of the class described, driving means, driven means, and means operatively connecting said driving and driven means comprising weight means pivotally connected to said driving means, weight means pivotally connected to said driven means, means pivotally connecting said weight means to each other, the axes of said pivotal connections being substantially parallel to the axis of rotation of said driving and driven means, resilient leaf spring means rigidly secured at one end thereof to one of said weight means and having the free end thereof in sliding contact with the other said weight means for resisting movement of both said weight means in response to centrifugal force during rotation of said driving and driven means, said resilient means being between said axis of rotation and said weight means and unconfined and free to flex throughout that portion of its length from the point of attachment on said one weight means to said free end thereof in response to movement of said weight means by centrifugal force, and the surface on said weight means engaged by said free end being a surface facing said axis of rotation, and means for limiting the movement of said weight means in response to centrifugal force.

WALTER J. SPENGLER.
